CLAIM

The ornamental design for footwear, as shown and described.

DESCRIPTION

FIG. 1 is an isometric view of the footwear.

FIG. 2 is another isometric view of the footwear of FIG. 1.

FIG. 3 is a front view of the footwear of FIG. 1.

FIG. 4 is a right side view of the footwear of FIG. 1.

FIG. 5 is a rear view of the footwear of FIG. 1.

FIG. 6 is a left side view of the footwear of FIG. 1.

FIG. 7 is a top view of the footwear of FIG. 1; and,

FIG. 8 is a bottom view of the footwear of FIG. 1.

The broken lines in the drawings denote environmental structure and boundaries that form no part of the claimed design.
